UNITED STATES PATENT OFFICE

EDGAR MERRITT BIDWELL, OF RIVERSIDE, ILLINOIS, ASSIGNOR TO WESTERN ELECTRIC COMPANY, INCORPORATED, OF NEW YORK, N. Y., A CORPORATION OF NEW YORK

METHOD OF AND APPARATUS FOR HANDLING STRAND MATERIAL

Application filed October 3, 1927. Serial No. 223,610.

This invention relates to methods of and apparatus for handling strand material, and more particularly to methods of and apparatus for drying traveling strand material, 5 such as pulp covered wire and the like.

In handling strand material for the purpose of drying, as for example in drying pulp covered wire after the wire has been passed through polishers care must be exercised in 10 order to prevent injurious distortion of the covering material during the drying operation. If the covered wire is subjected to any appreciable amount of bending or the covering thereof is engaged over an extended 15 portion of its surface as it is conducted through a drying oven or zone, there is a potential danger of producing a deleterious distortion or flattening of the soft pulp covering. Such distortion or flattening might result in the production of insulated wire which 20 does not meet the capacity requirements.

The primary objects of this invention are to provide a simple and efficient method of and a durable means for effectively handling 25 strand material with a minimum amount of bending of and engagement with the traveling material.

In accordance with the general features of the invention, one embodiment thereof includes an open or skeleton type of rimless capstan by means of which the improved method may be effectively practiced, which is rotatable within a drying chamber and provided with a plurality of strand engaging 35 chains positioned equi-distant from and spaced around the capstan axis. Strand material, such as a group of pulp covered wire of the type disclosed in Patent 1,615,416, is, issued on January 25, 1927, to Howard George 40 Walker and Albert Thomas March, may be directed from a plurality of polishers into the drying oven upon the chains which serve during the rotation of the capstan to move the groups of strands in uniform spaced relation lengthwise of the capstan axis, the

groups of strands being moved in opposite directions from a medial point. In this manner covered wire may be passed through the drying chamber without subjecting the material to deleterious bending or distortion. 50

These and other objects will be apparent from the following detailed description taken in connection with the accompanying drawings, wherein

Fig. 1 is a plan view of a strand handling apparatus representing one embodiment of the invention and by means of which the improved method may be efficiently practiced; 55

Fig. 2 is a side elevational view of the apparatus disclosed in Fig. 1, a portion of the 60 drying chamber being broken away to more thoroughly disclose certain of the capstan structures;

Fig. 3 is an end elevational view of the apparatus as viewed from the right in Fig. 2, 65 the upper and lower portion of the drying oven and capstan being shown in section in order to present a clear disclosure;

Fig. 4 is a detailed vertical sectional view of one of the capstan hubs taken on the line 70 4-4 of Fig. 3;

Fig. 5 is an enlarged fragmentary elevational view of the uppermost strand engaging chains shown in Fig. 3, and

Fig. 6 is a fragmentary plan view of the 75 structure disclosed in Fig. 5.

Referring now to the drawings wherein like numerals have been employed to designate similar parts throughout the various figures, it will be observed that one embodiment of the invention includes an open or skeleton type of strand receiving rimless capstan denoted generally by the numeral 10 which is mounted upon a rotatable shaft 11 within a suitable drying oven 12. The drying oven 12 is provided with inlet conduits 14 and an outlet conduit 15 which are designed to permit the free circulation therethrough of heated air. The skeleton capstan 10 includes a pair of flanged hub members 80 85 90

16 and 17 (Fig. 3) mounted in spaced relation upon the shaft 11 and secured to these hub members and extending radially therefrom are a plurality of supporting spoke-like frames 19. These spoke-like frames 19 are uniformly spaced about their respective hub members and are supported in their spaced relation by means of suitable frame members 20 (Fig. 2). The outer extremities of 10 companion supporting frames 19 provide a support for strand receiving chain mechanisms denoted generally by the numeral 21.

These chain mechanisms 21 include a pair of openly constructed conveyor chains 23 and 24 mounted between a pair of plates 25 arranged in parallelism and secured at the outer extremities of each set of companion supporting frames 19. At the outer extremities of each of the pairs of plates 25 is a stub shaft 27 which provides a bearing for a sprocket wheel 28. One of the sprocket wheels 28 meshes with the conveyor chain 24 as clearly shown in Fig. 5 and the other sprocket wheel 28 meshes with the chain 23, both of these 25 chains meshing with suitable sprocket wheels supported on a stub shaft 29 positioned medially of and extending between the plates 25. Medially of the lower reach of each of the chains 23 and 24 and meshing therewith 30 is a sprocket wheel 31 (Fig. 5) mounted upon a shaft 32 which carries a worm gear 33 at one extremity thereof. These worm gears 33 mesh with companion worms 35 mounted upon a shaft 36 which is provided at one extremity thereof with a bevel gear 37 which 35 meshes with a companion bevel gear 38. The gear 38 is supported at the outer extremity of a radial shaft 40 which supports a similar bevel gear 41 at its inner extremity and this 40 gear 41 meshes with a companion stationary gear 42, the hub of which provides a bearing for the rotatable shaft 11. From the foregoing it will be apparent that when rotation is imparted to the skeleton capstan 10 the 45 bevel gears 41 secured at the inner extremity of each of the shafts 40 will be rotated and hence the chains 23 and 24 will be moved in the direction indicated by the directional arrows (Figs. 3 and 5). It will be observed 50 that the upper reaches of the chains 23 and 24 move outwardly and horizontally from the medial shaft 29 and the individual links of these upper reaches of the chain are supported and guided by tracks or rails 44 which 55 are resiliently mounted at spaced intervals upon coiled springs 45 (Fig. 5). The outer surfaces of the links of the chains 23 and 24 are designed to engage strand material fed to the capstan 10 and are suitably curved at 60 the point of strand engagement to reduce to a minimum the amount of bending to which the strand is subjected as it is wound around the capstan.

Strand material such as strands of pulp 65 covered wire 46 after being drawn through

conventional polishing mechanisms denoted generally by the numeral 48 (Figs. 1 and 2) may be passed over an idler 49 provided with a sufficient number of grooves to maintain the entire group of strands in spaced relation. 70 This idler 49 is supported at the forward extremities of a pair of rocker arms 50 mounted upon a horizontal shaft 52 and the rearward extremities of the arms 50 support a suitable counterweight 53. The strands from the 75 idler 49 are directed downwardly around a second grooved idler 54 within the drying zone of the oven 12 (Fig. 2) and thence upon the inner portion of the upper reach of one of the chains 23 and 24, and upon continued 80 rotation of the capstan several turns are eventually wound upon the chains as shown in Fig. 5. At this point it is to be understood that the idler 49 is capable of receiving a supply of strand material from two sets of polisher mechanisms 48 and thus one group of strands may be directed onto the upper reaches of the chains 23 and the other group of strands onto the upper reaches of the chains 24. The strands initially engage the 85 inner portions of the chains 23 and 24 adjacent the shaft 27 and are urged outwardly therefrom upon rotation of the capstan. In the drawings each group of strands has been limited to ten, but obviously the apparatus 90 may be designed to handle a larger or smaller group of strands as the case may require. As the capstan 10 rotates within the drying oven 12 the groups of strands fed thereto are urged lengthwise thereof through the action of the 100 moving chains 23 and 24. In this manner each group of strands is uniformly passed through the drying oven in spaced relation and by reason of the open or ventilated design of the rimless capstan 10 the pulp covering may be readily dried without being subjected to extreme bending or distortion during the drying operation. 105

After the strands have been completely dried they are passed over an idler 56 (Fig. 110 2) and thence between the outer surface of a driven pulley 57 and the outer surface of a flexible belt 58 extending between a pair of pulleys 60 and 61. The belt 58 frictionally cooperates with the driven pulley 57 so as to 115 place a uniform and constant tension on the strands as they are being drawn from the capstan 10 and from this point the strands are directed to suitable take-up reels (not shown).

Rotation is imparted to the capstan 10 by means of the shaft 11 which has a bevel gear connection with a main drive shaft 63 (Figs. 1 and 3) which is connected with any suitable driving mechanism (not shown). The pulleys 57 are rotated by means of a shaft 64 upon which they are mounted and this shaft is rotated through a suitable worm and worm wheel connection which is connected with the main drive shaft 63 by means of a belt 125 120 130

65. In order to control the speed of rotation of the capstan 10 in accordance with the tension experienced by the strands as they are being drawn from the idler 49 a cone pulley 67 mounted upon the drive shaft 63 is employed (Figs. 1 and 3) which is connected with a companion cone pulley 68 positioned thereabove by means of a belt 69. The relative position of the belt 69 upon the pulleys 67 and 68 is controlled by shifter arms 71 fixed to the lower extremity of an arm 72 carried at one extremity of and depending from the shaft 52. It will be clear that when the tension on the strand 46 is increased the idler 49 will be lowered and the turning occasioned by the shaft 52 as the pulley 49 is lowered causes a shifting of the belt 69 so as to correspondingly reduce the speed of rotation of the capstan 10. Likewise, when the tension in the strands decrease the counter-weight 53 causes the idler pulley 49 to be carried upwardly with the result that the belt 69 will be shifted so as to correspondingly increase the speed of rotation of the capstan.

66. By employing the described apparatus for drying strand material, such as pulp covered wire, all the deleterious effects which necessarily result when the strand is subjected to excessive bending or pressure is eliminated. The amount of bending experienced by the strands as they pass around each of the conveyor chains is very slight and this slight bending is experienced only by a very small portion of the strands as distinguished from the bending and pressure experienced by coated wire which is passed over pulleys and the like. Thus by having an open or skeleton type of rimless capstan the strand may be engaged at intervals, thereby permitting the free circulation of heated air around the individual strands and the chains 23 and 24 serve very effectively to maintain the strands in spaced relation as they are uniformly drawn through the drying oven. Thus it will be understood that this invention provides a very simple and effective means for producing covered wire having a covering of desired uniform thickness.

67. Although the invention has been described in connection with the process of drying pulp covered wire, it is to be understood that the invention is capable of many other applications and should be limited only by the scope of the appended claims.

What is claimed is:

68. 1. The method of handling continuously traveling strand material, which consists in winding a plurality of strands of material, moving the turns of one strand laterally in spaced relation in a given direction from a predetermined winding position, and moving the turns of another strand in a direction opposite to the lateral movement of the first mentioned strand.

69. 2. In strand handling apparatus, a rimless

winding means, and means supported thereby movable relative to and substantially parallel with the axis of rotation of the winding means for supporting a turn of strand material.

70. 3. In strand handling apparatus, a rimless winding means, and means supported thereby movable relative to and substantially parallel with the axis of rotation of the winding means for supporting a turn of strand material, said supporting means being operable in response to the rotation of the winding means.

71. 4. In strand handling apparatus, a winding means, and means supported thereby movable relative to and substantially parallel with the axis of rotation of the winding means for moving turns of strand material in different directions.

72. 5. In strand handling apparatus, a strand drying chamber, an open type rimless winding means within the chamber, means for rotating the winding means, and means supported by the winding means for supporting a turn of strand material and for moving the strand across the winding means.

73. 6. In strand handling apparatus, a plurality of radial frame members rotatable about a common axis, and means carried at the outer portion of the frame members for supporting a turn of strand material and for effecting the movement of the turn in a direction substantially parallel with the axis of rotation.

74. 7. In strand handling apparatus, a rimless strand winding means, and endless means supported thereby for engaging a turn of strand and for moving a turn of strand material in a direction substantially parallel to the axis of rotation of the winding means.

75. 8. In strand handling apparatus, a strand winding means, endless means supported thereby for engaging a turn of strand material and for moving it in a given direction, and a companion endless means for engaging a turn of strand material and for moving the turn in a direction opposed to the movement of the first mentioned turn.

76. 9. In strand handling apparatus, a plurality of radial frame members rotatable about a common axis, and means carried at the outer portion of the frame members for supporting turns of strand material and for effecting the movement of such turns in different directions during the rotation of the frame members.

77. 10. In strand handling apparatus, a plurality of radial frame members equally spaced and rotatable about a common axis, and endless conveyor members supported at the outer extremity of each frame member for receiving a turn of strand material and for moving the strand at right angles to the radial frame member, said conveyor members being

operable in response to the rotation of the frame members.

11. In strand handling apparatus, a strand winding means, means carried thereby comprising an endless conveyor for engaging the strand material and for moving turns thereof across the winding means, and means for resiliently supporting the portion of the conveyor which engages the turns of the strand material.

¹⁰ In witness whereof, I hereunto subscribe my name this 24 day of September, A. D. 1927.

EDGAR MERRITT BIDWELL.
